UNITED STATES PATENT OFFICE.

FREDERICK MORRISON AND FOREST W. MAYS, OF HUNTINGTON, WEST VIRGINIA.

CLAMP FOR BATTERY CONNECTIONS.

Application filed May 5, 1923. Serial No. 636,848.

To all whom it may concern:

Be it known that we, FREDERICK MORRISON and FOREST W. MAYS, citizens of the United States, residing at Huntington, in the county of Cabell and State of West Virginia, have invented certain new and useful Improvements in Clamps for Battery Connections, of which the following is a specification, reference being had to the accompanying drawings.

This invention relates to battery clips or clamps by which a wire may be attached to the terminal or post of the battery.

The general object of the invention is to provide a clamp of this character by which the wire may be connected readily to the post or disconnected therefrom, and which is so constructed that a good electrical connection will be made with the battery post.

20 A further object is to provide a clamp of this character which is very simple, which may be quickly applied and quickly removed, and which may be cheaply constructed.

25 Other objects will appear in the course of the following description.

Our invention is illustrated in the accompanying drawings, wherein:—

Figure 1 is a perspective view of our battery clamp in use;

Figure 2 is a longitudinal sectional view of the clamp closed;

Figure 3 is a like view to Figure 2 but showing the clamp opened.

35 Referring to these drawings, it will be seen that our improved clamp comprises two opposed members 10 and 11. The member 10 at its middle is formed with a lug 12 which is reduced in thickness and the

40 member 11 at its middle is formed with the two ears 13 which are adapted to embrace the lug and receive through them a pivot pin or bolt 14 whereby the two members are pivotally connected to each other. The

45 members 10 and 11 are formed at one end with the complementary or opposed jaws 15. The member 10 is extended rearward beyond its pivot 14, as at 16, and this rearwardly extending portion on its inner face is longitudinally recessed, as at 17, the end of this

50 portion 16 having a recess 18 intersecting the recess 17. The member 11 upon its inner face confronting the recessed portion of the member 10 is recessed, as at 19, this recess

55 being longitudinal. The member 11 is extended beyond the member 10 to form a

tubular socket 20 for the reception of the cable or conductor 21. The extended portion of the member 11 may be split longitudinally and then folded over and clamped down upon the cable or any other suitable means may be used to electrically connect the bared end of the cable into the socket 20.

Coacting with the members 10 and 11 and operating within the recesses 17 and 19 is 65 a cam 22 having a handle 23. When this

cam is inserted between the recesses 17 and 19 and the handle is turned into parallelism with the rear end of the member 11, the

cam will act to force the rear end of the member 10 outward and the opposed jaws 15 against each other. It will be seen that

the cam is so formed that when the handle 23 is turned down into parallelism to the shank of the member 11 that the eccentric 75

will have turned slightly past the center so that the cam will be held in this position until it is forcibly moved back. It has not been found necessary to pivot this cam to

one or the other of the members 10 or 11, 80 for so long as the jaws 15 are clamped upon a post 24 and the cam is in the position shown in Figure 2, the cam cannot be withdrawn. By turning the handle 23 outward

so that it passes into the slot 18, the jaws 85 may be opened so as to readily remove the clamp from the battery post.

We do not wish to be limited to any particular manner of forming these elements 10 and 11. Preferably these members will 90 be made of copper so as to secure good conduction and a thorough electrical connection between the cable 21 and the post 24.

We claim:—

1. A battery connector clamp of the character described comprising two opposed members pivoted to each other, each of said members being formed at one end with a jaw, the jaws confronting each other, one of said members extending beyond the pivotal point and being formed to embrace a cable and both of said members having longitudinally extending confronting recesses, and a cam disposed in said recesses and having a handle, said cam, when the handle is shifted into a position parallel to one of said members, acting to force the jaws together and when shifted in the opposite direction permitting the jaws to be opened.

110 2. A battery connector clamp of the character described comprising two opposed

members pivoted to each other, the members on one side of the pivot being formed with confronting jaws and said members extending beyond the pivot at the ends opposite said jaws, both of said members having confronting recesses rearward of the pivot and one of said members being extended beyond its recess and formed to provide a socket to receive an electric connector, and a cam disposed within the confronting recesses and having a handle, said cam when turned in one direction by the handle acting to force the rear ends of the members apart from each other and the jaws toward each other and when turned in another direction permitting the rear ends of the members to be shifted toward each other and the jaws opened.

3. A battery clamp of the character described comprising complementary members having pivotal engagement with each other

between their ends, said members on one side of the pivot being formed with confronting jaws and the inner faces of said members rearward of the pivot being formed with confronting recesses, the recess in one member intersecting a recess extending inward from the outer edge of the member, the other member having its rear end longitudinally extended and formed to provide a split socket to receive a cable connector, and a cam disposed within said recesses and adapted when shifted in one direction to force the rear ends of the members apart and their jaw ends together and in the other direction to permit the jaws to open, said cam having a handle.

In testimony whereof we hereunto affix our signatures.

FREDERICK MORRISON.
FOREST W. MAYS.
